Inc., St. Paul, Minn., a corporation of Minne-
sota

Application May 12, 1947, Serial No. 138,980

Term of patent 3½ years

(Cl. D80—5)

To all whom it may concern:

Be it known that I, Lewis Fine, a citizen of the United States, residing at Saint Paul, in the county of Ramsey and State of Minnesota, have invented a new, original, and ornamental Design for a Display Case for Bottles or the Like, of which the following is a specification, reference being had to the accompanying drawing, forming part thereof.

Fig. 1 is a front view of a display case showing my new design, with one of the levers in a depressed position;

Fig. 2 is a top plan view of the display case;

Fig. 3 is a side view of the display case from the right side thereof.

The bottles shown in the figures in dotted lines are for illustrative purposes only. The back of the display case is substantially plain.

I claim:

The ornamental design for a display case for bottles or the like, as shown and described.

LEWIS FINE.
